[57] CLAIM

The ornamental design for a removable hard disk drive module, as shown and described.

DESCRIPTION

FIG. 1 is a top, front, left side perspective view of a removable hard disk drive module showing our new design within its intended operating environment of a host computer;

FIG. 2 is a front elevational view thereof on an enlarged scale;

FIG. 3 is a top plan view thereof on an enlarged scale;

FIG. 4 is a right side elevational view thereof on an enlarged scale;

FIG. 5 is a left side elevational view thereof on an enlarged scale;

FIG. 6 is a bottom plan view thereof on an enlarged scale;

FIG. 7 is a rear elevational view thereof on an enlarged scale.

The computer host shown in broken lines in FIG. 1 is for illustrative purposes only and forms no part of the claimed design.
